UNITED STATES PATENT OFFICE.

PIERRE DANSEREAU, OF MONTREAL, CANADA.

AXLE-NUT.

SPECIFICATION forming part of Letters Patent No. 738,417, dated September 8, 1903.

Application filed April 2, 1903. Serial No. 150,697. (No model.)

To all whom it may concern:

Be it known that I, PIERRE DANSEREAU, a subject of the King of Great Britain, residing in the city and district of Montreal, Province 5 of Quebec, Canada, have invented certain new and useful Improvements in Axle-Nuts; and I do hereby declare that the following is a full, clear, and exact description of the invention, such as will enable others skilled in 10 the art to which it appertains to make and use the same.

My invention relates to axle-nuts; and my object is to provide a simple arrangement for retaining a wagon-wheel in position upon its 15 spindle and to provide for adjusting the retaining-nut in a simple manner, so as to take up the wear which takes place at this part.

The invention consists in the construction and combination of parts to be more fully described hereinafter, and definitely set forth in the claim.

In the drawings, which fully illustrate my invention, Figure 1 is a perspective view representing the sleeve of a wheel-hub, a portion 25 of which has been broken away, as illustrated. Fig. 2 is a perspective showing a collar used in connecting the parts. Fig. 3 represents, also in perspective, the hub-nut. Fig. 4 represents in perspective a washer. 30 Fig. 5, which is also a perspective, represents the cap-nut. Fig. 6 represents in perspective a portion of the axle, showing the spindle with the sleeve, &c., removed. Fig. 7 is a vertical longitudinal section through 35 the spindle and hub-sleeve, showing all the parts in their assembled relation.

It should appear that Figs. 1 to 5 of the drawings represent the parts substantially in the order in which they are applied to the 40 spindle.

Throughout the drawings and specification the same numerals of reference indicate like parts.

Referring more particularly to the parts, 45 10 represents an axle provided with the usual shoulder 11, beyond which is formed the spindle 12, which spindle has a reduced extension 13, which is provided with threads 14 for a portion of its length, and it should appear that this extension is mutilated or cut 50 away so as to have a flat face 15. An oil-groove 16 may be formed in the lateral sur-

face of the spindle 12, as indicated. It should appear that adjacent to the extension 13 the spindle 12 is formed into an annular shoulder 55 17. A hub-sleeve 18 is adapted to be applied to the said spindle in the manner indicated in Fig. 7. It should appear that this sleeve is of a common form, having an inner bore 19 of substantially the diameter of the spindle 12 and 60 an enlarged bore or mouth 20, provided with an internal thread, as indicated, the enlarged bore 20 being connected with the reduced bore by a conical shoulder 21, as shown. After this sleeve 18 has been applied to the 65 spindle in the manner shown a collar 22 is applied to the reduced extension 13. It should appear that this collar comprises a body 23 of substantially cylindrical form having an incomplete bore 24, whereby a 70 flat face 25 is formed. This collar has a head 26 of enlarged diameter and a conical shoulder 27, as shown. It should be understood that this collar is applied to the reduced extremity of the spindle in the manner shown in 75 Fig. 7, so that the flat face 25 rests upon the flat face 15, the inner extremity of the body 23 resting adjacent to the aforesaid shoulder 17. When so applied, the conical face 27 abuts against the conical shoulder 21 aforesaid, and this collar from this arrangement affords means for retaining the sleeve 18 in 80 position. The hub-nut 28 is then applied, being received by the threads 14 aforesaid, and, as will be readily understood, it is expected to maintain the collar 22 in position. It consists, substantially, of a body 29, preferably of hexagonal form, having an annular shoulder or head 30, providing an inner face 31, which is adapted to rest against the outer 90 face of the collar 22, as indicated. The lateral faces 32 of this nut are provided with elongated openings or recesses 33, which are disposed longitudinally with reference to the axis of the nut and which extend through to 95 the bore 34 of the nut at the outer face 40 thereof. These openings or recesses 33 are for the purpose of effecting an adjustment of the nut and for retaining the same in different positions. For this purpose they coöperate with a small split pin 35, which is inserted in a transverse opening 36, which passes diametrically through the threaded extension 13, as illustrated most clearly in Figs. 6 and 100

7. As will be readily understood, this pin is adapted to pass through a pair of the diametrically opposite openings. Evidently to effect an adjustment of the nut it is necessary 5 only to remove the pin and to turn the nut in either direction to the desired amount, bringing a second pair of the openings 33 into alignment with the opening 36 and replacing the pin as before. After these parts have been 10 assembled in the manner described a cap-nut 37 may be screwed into the threaded bore 20 of the hub-sleeve 18, the washer 38 being first applied to the extremity of the sleeve, as indicated. It should appear that this cap-nut 15 37 has an internal bore or chamber 39, which receives the aforesaid nut 28 and the threaded extension 13 of the spindle.

It should appear that in the manner described a very simple arrangement is provided 20 for maintaining the hub in position and at the same time enabling necessary adjustments to be quickly made when desired. Evidently the cap-nut 37 affords means for preventing any possibility of the accidental removal or displacement of the split pin 35 unless the cap-nut 37 has been first removed.

Upon reference to Figs. 6 and 7 it will be seen that the spindle 12 is formed with an annular groove 15^x at a point about midway 25 the length of the flattened portion 15, and the collar 22 is so disposed when in position that the head 26 thereof extends partially across said groove, as seen in Fig. 7, the collar not fitting snugly to the spindle, as is 30 shown in said figure, thus permitting the lubricant to readily find access to all parts of

the journal and to the hub-nut and the threads on the spindle with which said hub-nut is engaged.

Having described my invention, what I 40 claim as new, and desire to secure by Letters Patent, is—

The combination with the spindle having reduced extension with screw-threads, flattened portion, annular groove intersected by 45 said flattened portion, shoulder and transverse opening, of a sleeve inclosing said spindle and having enlarged mouth with internal threads, and a conical shoulder, a collar having a bore with flattened face conforming to 50 the flattened portion of said extension, an enlarged head extending partially across said groove, and a conical shoulder engaging the conical shoulder of said sleeve, a cap-nut threaded upon the threaded portion of said 55 extension and having lateral faces with longitudinally-disposed openings, a spring-pin passed through said openings and through the opening in said extension, a washer bearing against the outer end of said sleeve and 60 a cap-nut having threaded extension engaging the internal threads of the mouth of said sleeve, and a flange engaging the outer face of said washer, the parts all being arranged, constructed and operating, substantially as 65 shown and described.

In witness whereof I have hereunto set my hand in the presence of two witnesses.

PIERRE DANSEREAU.
